J. LYLE,
BUNCH BUILDER ATTACHMENT,
APPLICATION FILED MAR. 11, 1915.

Patented Aug. 10, 1915.

UNITED STATES PATENT OFFICE.

JESSE LYLE, OF DANVILLE, VIRGINIA, ASSIGNOR OF ONE-THIRD TO SAMUEL S. EPPERSON AND ONE-THIRD TO H. L. PRITCHETT, BOTH OF DANVILLE, VIRGINIA.

BUNCH-BUILDER ATTACHMENT.

1,149,930.

Specification of Letters Patent. Patented Aug. 10, 1915.

Application filed March 11, 1915. Serial No. 13,665.

To all whom it may concern:

Be it known that I, JESSE LYLE, a citizen of the United States, residing at Danville, in the county of Pittsylvania and State of Virginia, have invented certain new and useful Improvements in Bunch-Builder Attachments, of which the following is a specification.

This invention relates to improvements in spinning machines and more particularly to bunch builder attachments for the builder motions thereof.

The object in view is the retardation of the builder motion let-off for reducing the length of the traverse at the beginning of the bobbin winding operation for producing a "feeler" bunch, and the automatic release of the builder motion let-off for enabling the ring rail to have full traverse at the completion of the bunch.

With this and further objects in view, as will in part become apparent and in part be stated, the invention comprises certain novel constructions, combinations, and arrangements of parts as will be subsequently specified and claimed.

In the accompanying drawing: Figure 1 is a fragmentary side elevation of part of a spinning machine embodying the features of the present invention. Fig. 2 is an enlarged detail, sectional elevation taken on the plane indicated by line 2-2 of Fig. 1 and looking in the direction indicated by the arrow. Fig. 3 is a sectional elevation of the let-off control rods detached. Fig. 4 is a similar view of a modified form of one of the rods. Figs. 5 and 6 are detail perspective views of different length control sections adapted for substitute use for varying the size of the bunch.

Referring to the drawing by numerals, 1 indicates an ordinary spinning frame, having the usual supporting bars 2, 2, brackets 3, rock shaft 4 journaled therein, and rocker lever 5 carried by the rock shaft and provided with a counter balance weight 6 and the usual stroke stand 7, which may be connected by a link 8 to a like stroke stand not illustrated. The lever 5 has the usual rocker arm 9 sustaining and actuating the pusher rod 10, which engages and operates the ring rail 11, provided with the usual yarn guides for delivering yarn to the bobbins 12. A builder motion of the screw actuated let-off type is provided for actuating the stroke

stand 7, and so far as the builder motion itself is concerned, it is of the ordinary form, as are all of the parts above described, the builder motion consisting of a swinging lever 13, actuated by a cam or other appropriate gear, not illustrated. Lever 13 is of usual form and bears a rotatably mounted screw shaft 14, on which is threaded a traveling block 15. One end portion of screw 14 is engaged by the regular let-off mechanism of the builder motion consisting of a ratchet wheel 16 engaged by pawl 17, carried by the usual lever 18 pivoted to the outer end of shaft 14 and having a pivotal connection at 19 to the frame of the machine, so that as the lever is successively swung up and down, the pawl 17 will impart successive steps of rotation to the shaft 14, and thereby feed the block 15 along the lever 13. The said block is engaged by a chain 20, which extends longitudinally of shaft 13 and is passed about an idler pulley 21, journaled on the lever 13.

The chain 20 extends upward from pulley 21 and is connected to the usual whirl 22, journaled in the bracket 23, and in turn having its smaller cam or disk engaged by a chain 24 which extends to and is connected with the stroke stand 7, it being understood that the chain 20 engages the larger disk or cam of whirl 22, whereby in the ordinary operation of the structure described thus far, all of the parts of which are of the usual form, the successive strokes of the lever 13 will impart corresponding strokes to the pusher rod 10 and thence to the ring rail 11, whereby the requisite traverse is afforded, while at the same time, the successive steps in the let-off of chain 20 due to

the movement of block 15 along shaft 14, incident to the step by step rotation of ratchet wheel 16, enable the stroke stand 7, to have successive gains which provide for the usual gain of the ring rail, whereby the ordinary form of winding for the several bobbins is provided, the traverse and gain being maintained uniform throughout the building of the bobbin. The automatic looms, however, as is now well known, are provided with feeler mechanism for actuating the bobbin ejecting and new bobbin supplying mechanism, and this feeler mechanism depends on its operation for the presence of a "bunch" substantially at the point of exhaustion of supply of yarn on the bob-

bin.

100

110

bin. The mechanism described above would not produce such a bunch, and various attempts have been made to provide mechanism which will produce a bunch, although it is believed that no effective automatic bunch builder for the particular screw controlled let-off described has been produced, and it is one of the objects of this invention to provide such a bunch builder incident to the control of this type of builder motion. To this end, a tubular rod 25 is pivoted to a part of the frame-work, as for instance, to one of the bars 2 in position to depend toward the builder motion, and telescoped within rod 25 is a rod 26 whose lower end is pivotally connected to a chain 20 as by the pin fixed to the chain and passed through an eye 26' formed at the lower end of the rod 26. The upper or tubular rod 20 may be pivotally mounted in any appropriate manner as by a pivot pin passed through an eye 25' at the upper end of the rod. The rod 25 is closed at its upper end, and arranged within the bore of rod 25 is a controlling section of rod 27, which is located to limit the inward thrust of rod 26 axially of rod 25. To vary the distance of this thrust, the section 27 is provided with an axially arranged screw 28 adapted 30 to be locked by a radial screw 29. By setting the screw 28 at any given point of longitudinal adjustment, the abutting of the inner or upper end of rod 26 against the head of the screw 28 when the section 27 has its upper end resting against the closed end of rod 25, will positively limit the extent of inward or upward thrust of rod 26. As seen in Figs. 5 and 6, instead of varying the effective length of the section 27 by the use of the screw 28, a short control section 27' may be used when a long stroke of rod 26 is desired, and a long control section 27" may be employed when a short stroke of rod 26 is required, and the relative lengths of 40 the control sections may be varied as desired, it being, of course, understood that only one section is used at any one time. In lieu of providing a control section 27, the lower rod may, as indicated in Fig. 4, 45 be constructed in the form of rod 26'', having an axially located screw 28' adapted for longitudinal adjustment to take up the space otherwise occupied by the section 27, whereby the function of the section 27 as 50 to its adjustability, is provided without the necessity for providing a separate loose part.

In operation, when the block 15 is at its rearmost position and the ring rail 11 is 55 starting its first stroke, the rod 26 will be given an upward thrust and will move within rod 25 until the control section 27 strikes the closed upper end of rod 25, or the equivalent of section 27 strikes this part, 60 and, thereupon, the rod 26 will enter no

further, and its protruding end with its pivotal engaging eye 26' will prevent the chain 20 from moving on up with the balance of the stroke of the builder motion so that only a small fragment of the otherwise delivered reciprocal movement of the chain 70 is actually delivered thereby. The ring rail 11, therefore, is given only a relatively short traverse in the same length of time which would ordinarily be required to make the 75 full traverse. The result is that the yarn which would ordinarily be delivered for a full stroke of the ring rail, is delivered in a bunch, and it requires only two or three of such abbreviated strokes to develop the 80 required feeler bunch. It is to be observed that the pivot of rod 25 is so located that as the block 15 progresses along the shaft 14, and the chain correspondingly progresses, the pivot engaging eye 26' moves 85 away from the axial plane of the pivot of rod 25 so that after the first few strokes of the builder motion (enough to complete the required feeler bunch) the pivot engaging eye 26' will have moved sufficiently away 90 from the axial plane of the pivot of rod 25 as to allow rod 25 and rod 26 to swing vertically to an extent permitting the chain 20 to remain straight between block 25 and pulley 21, whereupon, the movement imparted by the chain 20 becomes normal, and the traverse of the ring rail 11 accordingly becomes full and remains the same throughout the balance of the winding of the bobbins. The gain is, of course, proportionately affected since during the retardation incident to the deflection of chain 20 by rods 25 and 26, the effect of the operation of the let-off mechanism is practically nullified, and the bunch is built substantially 95 without gain, whereas, as soon as the pivot of rod 26 moves to the position allowing the full operation of the builder motion, the gain becomes constant just the same as the 100 traverse becomes constant. 105

What I claim is:

1. The combination, with the builder motion of a spinning machine, of pivotally mounted telescoping rods pivotally connected to a portion of the builder motion 115 for restricting the extent of effective movement of the initial strokes of the builder motion.

2. The combination, with the builder motion of a spinning machine, of pivotally mounted telescoping rods pivotally connected to a portion of the builder motion for restricting the extent of effective movement of the initial strokes of the builder motion, and means for varying the extent of 125 relative telescopic action of said rods.

3. The combination, with the builder motion of a spinning machine, of pivotally mounted telescoping rods pivotally connected to a portion of the builder motion 130

for restricting the extent of effective movement of the initial strokes of the builder motion, and adjustable means carried by one of the rods and disposed to engage the other for varying the extent of relative telescopic action of the rods.

4. The combination, with the builder motion of a spinning machine, of pivotally mounted telescoping rods pivotally connected to a portion of the builder motion for restricting the extent of effective movement of the initial strokes of the builder motion, and a screw adjustable longitudinally of one of the rods and disposed to interrupt telescopic movement of the rods with respect to each other.

5. The combination, with a builder motion of a spinning machine, of a swinging rod, and a rod telescoping therewith and connected with a portion of the builder motion for restricting the extent of effective movement of the initial strokes of the builder motion.

6. The combination, with the builder motion of a spinning machine, of a swinging

rod, and a rod telescoping therewith and connected with the let-off chain of the builder motion for restricting the extent of effective movement of the initial strokes of the builder motion.

30

7. The combination, with the builder motion of a spinning machine, of a swinging rod, and a rod telescoping therewith and connected with the let-off chain of the builder motion for restricting the extent of effective movement of the initial strokes of the builder motion, the pivot of the first mentioned rod upon which it swings being located for having the point of connection of the second mentioned rod with the chain 40 move sufficiently away from the axial plane of said pivot for releasing the chain of restriction in effective movement by said rods.

In testimony whereof I affix my signature in presence of two witnesses.
